UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

RAILWAY SIGNAL TORPEDO.

1,421,188.

Specification of Letters Patent. Patented June 27, 1922.

Application filed April 25, 1921. Serial No. 464,110.

To all whom it may concern:

Be it known that I, FRANK DUTCHER, a citizen of the United States, residing at Versailles, in the county of Allegheny and State 5 of Pennsylvania, have invented certain new and useful Improvements in Railway Signal Torpedoes, of which the following is a specification, reference being had therein to the accompanying drawings.

10 This invention relates to improvements in railway signal torpedoes, and their manufacture, but relates more particularly to railway signal torpedoes in which the explosive powder is carried in a paper container or case, the ends of which are closed by being crimped, and which is provided with a railway rail engaging member or strap for fastening the torpedo to the railway track.

15 The object of this invention is to provide a railway signal torpedo so constructed that when it is exploded there will be no flying particles to cause damage or injury.

Another object of this invention is to 20 make the torpedo case of an angular shape so that there will be presented a flat side to which the rail-engaging member can be attached and upon which it will rest when fastened upon a railway rail.

25 A further object of this invention is to provide a railway signal torpedo which is so constructed that it is cheap and simple of manufacture and at the same time highly efficient in use.

30 Other objects and novel features of this invention relating to both manufacture and construction will appear in the following description and drawings.

In the drawings:

35 Figure 1 is a perspective view of a railway signal torpedo embodying my invention, the case being shown octagonal in shape.

40 Fig. 2 is a perspective view of the several 45 parts of the torpedo case, the wad, and the rail engaging member in separated and un-assembled relation.

45 Fig. 3 is a longitudinal sectional view of the torpedo shown in Fig. 1.

50 Fig. 4 is a vertical sectional view taken on the line 4—4 of Fig. 3.

55 Fig. 5 is a perspective view of a torpedo embodying my invention, the torpedo case being shown to be round in shape.

Fig. 6 is a vertical sectional view on the 55 line 6—6 of Fig. 5.

Fig. 7 is a longitudinal vertical section of the apparatus used to hold the torpedo wrappers while being filled with their explosive charge.

Fig. 8 is a side elevation of the explosive measuring and filling buckets.

Fig. 9 is a top plan view of the explosive measuring and filling buckets.

In the accompanying drawings, like parts 65 are designated by similar reference numerals throughout the description.

To those skilled in the art of the manufacture of railway signal torpedoes, it is well known that great hazard and danger 70 are involved from both fire and explosion, and that due to the great care which must necessarily be taken, the manufacturing cost is high.

My invention involves both the manufacture of, and the completed torpedo, with 75 novel improvements in both. The preferable form of my improved torpedo is shown, Figs. 1 to 4 inclusive, with an octagonal shaped wrapper and case. With a case of 80 this shape the torpedo has a plurality of flat sides and therefore when it is placed upon a railway rail it will not have a tendency to roll when struck by the moving wheel of a locomotive. This case has in addition the advantage of providing a flat side upon which the rail engaging member is secured.

85 As shown in Figs. 5 and 6, this torpedo can be made with a round case if desired, 90 and I do not limit my invention to the particular shape of case used.

95 In constructing a torpedo of the type shown in Figs. 1 to 4, inclusive, I provide an octagonal explosive wrapper 1, provided with extending portions 1^a and 1^b. The end 1^a of the wrapper 1 is first spun or crimped in, as shown at 2, and the wrapper is then placed with its open end 3, Fig. 7, upward in octagonal shaped openings 4 in a base-board 5. Suitably supported above the base 5 and adjacent the open ends 3 of the explosive wrappers 1 is a member 6 provided with funnels 7 so positioned that their spouts 8 project through the member and into the 100 open ends of the wrappers, as shown.

105 To facilitate the charging or loading of the explosive wrappers with the explosive

powder A, I have provided a rod 9, having at its opposite ends the handles 10. Spaced at distances, equal to the distances between the funnels 7, along the rod 9, are a plurality of buckets 11, provided with scoop-like ends 12. Each bucket is constructed to hold just the correct amount of explosive powder to fill one of the torpedo wrappers.

In operation the handles 10 are grasped 10 and the buckets 11 scooped full of powder from a bin or the like (not shown) and the powdered explosive is dumped from the buckets into the several funnels 7, and thus several explosive wrappers are charged 15 simultaneously. Due to the fact that the spouts 8 of the funnels project into the wrappers, no powder is left upon the extending ends 1^b of the wrappers.

After the wrappers have been charged, 20 as described above, a paper or cotton wad 13 is placed in the end of each upon the powder therein to prevent the possibility of spilling any of the explosive while the wrappers are being handled and their ends 25 1^b are being spun or crimped in, as shown at 14. Because of the method of loading and the use of the wad 13, there is no loose powder upon or within the extending ends 1^b of the wrappers, which if it were present 30 might possibly be exploded by engagement with the tool used to spin or crimp these ends.

With the wrapper 1 loaded and crimped, the rail engaging member or strap 15 is 35 now placed upon one of its flat sides and the octagonal case 16 is slid upon and over both of them. The case 16 is made of a size to fit the wrapper snugly and will therefore bind the rail-engaging member 40 firmly in place between the wrapper and the covering case.

If desired, the torpedo can be safely 45 guarded against dampness by dipping it into a waterproof bath.

It will be readily understood that in 50 making the round form of torpedo shown in Figs. 5 and 6, the method and procedure are similar to that used in making the octagonal form. In this form, I have the inner 55 wrapper 20 with its ends crimped in as at 21, and the rail-engaging or attaching member 22 carried upon the wrapper between it and the covering case 23.

Not limiting myself to the particular 60 shape of torpedo case, neither do I limit myself to the use of the particular rail-engaging member shown in the drawings, as a spring clip or other similar and well-known type of rail attaching means can be readily adapted to use with my torpedo.

From the foregoing description it will be seen that I have provided a railway signal 65 torpedo so constructed as to prevent the flying of particles when exploded. This advantageous result is accomplished by crimp-

ing the ends of the explosive wrapper so that when the torpedo is struck by a moving wheel and exploded, the ends of the wrapper blow open and not away, this action being assisted by the fact that the case 70 begins to mash, which mashing tends to start the opening of the crimped ends, under the wheel before the explosion occurs.

In addition to the above improvement, I 75 have provided a safe and novel means of loading a plurality of torpedo wrappers simultaneously and so constructing the several parts comprising the torpedo that a rail attaching means can be quickly and cheaply attached thereto.

Having thus described my invention, what I claim and desire to secure by Letters Patent is:—

1. A railway signal torpedo comprising a wrapper, having extending end-portions, 85 the extending end portions crimped inward, an explosive within the wrapper, a case embracing the wrapper, and a rail-engaging member carried between the wrapper and its case.

2. A railway signal torpedo comprising an explosive carried within a wrapper having inwardly crimped ends, a case embracing the sides of the wrapper, and a rail-engaging member carried upon the wrapper 95 and beneath the case.

3. A railway signal torpedo comprising an explosive carried within a wrapper having inwardly crimped ends, a wad within one end of the wrapper, a case embracing the wrapper, and a rail-engaging member carried upon the wrapper and beneath the case.

4. A railway signal torpedo comprising a wrapper of octagonal shape in cross-section, 105 an explosive held within the wrapper by crimping its ends inward, a case embracing the wrapper, and a rail-engaging member carried upon the wrapper and beneath the case.

5. A railway signal torpedo comprising a wrapper having a plurality of flat sides, the ends of the wrapper crimped inwardly to retain an explosive therein, a rail-engaging member carried upon one of the flat 115 sides of the wrapper, a case similar in cross-sectional shape to the wrapper, and the wrapper and rail engaging member carried within the case, for the purpose described.

6. A railway signal torpedo, comprising 120 a wrapper having a plurality of flat sides, the wrapper provided with extending end portions crimped inward, an explosive within the wrapper, an open ended case embracing the wrapper, and a rail-engaging member carried between the wrapper and the case.

7. A railway signal torpedo comprising a wrapper having a plurality of flat sides, 125 the wrapper provided with extended end 130

portions crimped inward, an explosive within the wrapper, an open ended case embracing the wrapper, and a rail-engaging member carried by the torpedo.

5. 8. A railway signal torpedo comprising a wrapper having a plurality of flat sides, the ends of the wrapper crimped inwardly to retain an explosive therein, a case similar in cross-sectional shape to the wrapper, 10 the wrapper carried within the case and a rail-engaging member carried by the torpedo.

9. A railway signal torpedo comprising a wrapper of octagonal shape in cross-section, an explosive held within the wrapper 15 by crimping its ends inwardly, a case embracing the wrapper, and a rail-engaging member carried by the torpedo.

10. A railway signal torpedo comprising

an explosive within a wrapper having 20 crimped ends, an open ended case around the explosive, and a rail-engaging member carried between the explosive and the case.

11. A railway signal torpedo comprising an explosive within a wrapper having 25 crimped ends, an open ended case around the explosive, and a rail-engaging member carried by the torpedo for securing the same to the head of a railway rail.

12. A railway signal torpedo comprising 30 an explosive within a wrapper having crimped ends, a case around the explosive, and a rail-engaging member carried by the torpedo, for the purpose described.

In testimony whereof I hereunto affix my 35 signature.

FRANK DUTCHER.
